UNITED STATES PATENT OFFICE.

PETER G. SCHMIDT, OF TUMWATER, WASHINGTON.

GAS-PRODUCER.

No. 910,319.

Specification of Letters Patent.

Patented Jan. 19, 1909.

Application filed March 7, 1908. Serial No. 419,680.

To all whom it may concern:

Be it known that I, PETER G. SCHMIDT, a citizen of the United States, and a resident of Tumwater, in the county of Thurston and 5 State of Washington, have invented certain new and useful Improvements in Producers, of which the following is a specification.

My invention is an improvement in gas producers and consists in certain novel constructions and combinations of parts to be hereinafter described and claimed.

The object of my invention is to provide an apparatus to be used in gas producers, to remove the products of distillation from the 15 parts of the producer not in the direct line of draft and outside of the zone of decomposition, and to conduct said products into and through such zone.

Referring to the drawings forming a part 20 hereof Figure 1 is a sectional view of a producer provided with the improvement, and Fig. 2 is a section of the upper part of another form of producer with which the improvement is adapted to be used.

25 In the present embodiment of my invention, the producer 1 is provided with the movable grate 2 and the fixed shield 3, through which pass the products of decomposition into the collector pipe 4, and to the 30 transverse pipe 5. The shield is provided with openings 13 registering with openings 14 in the wall of the producer, and closed by doors 15. The object of the openings 13 and 35 14 is to permit inspection of the combustion zone, and to permit the removal of clinkers through said openings.

The producer is provided with the cover 6, having an annular flange 7 depending into the water seal 8, and the cover is provided 40 with a flanged feed opening 9, closed by a cover 10, having a depending flange 11, engaging the water seal 12.

In the operation of the producer just described, the products of decomposition pass upwardly through the shield, or downwardly 45 through the grate as the case may be, depending upon the direction of the draft. In either case that portion of the material upon the grate and just above the zone of decomposition, is subjected to more or less heat, and as a consequence more or less volatile products are distilled therefrom, which products pass to the upper part of the producer.

A pipe 16 extends through the side wall of

the casing, the said pipe being provided with 55 an upwardly extending lateral extension 17, opening near the top of the casing. The outer end of the said pipe communicates with a vertical pipe 18, which at its lower end communicates with a horizontal pipe 19, extending 60 into the casing and communicating with the space beneath the grate as at 20. The pipe 16 extends beyond the pipe 18, and is provided with a packing nut 21, through which extends a rod 22, provided at its outer 65 end with a handle 23, and at its inner end with a piston 24. The upper end of the pipe 18 and the outer end of the pipe 19, are provided with similar packing nuts 21, and with pistons 24 operated by rods 22. The pistons 70 24 are for the purpose of freeing the pipes 16, 18 and 19 from the condensed products. The operation of the pistons will be evident from the description, and it is not thought necessary to further describe the same. A 75 valve 25 is provided in the pipe 18, and a by-pass connects the portions of the pipe on each side of the valve, the by-pass comprising a body portion 26 in which is interposed an exhauster 27, and arms 28 and 29 provided 80 with valves 30, 31 respectively. A pipe 32 leads from the arm 29 extending transversely of the casing as at 33, and upwardly as at 34 to the pipe 5, the pipe being provided with a valve as at 36 for a purpose to be presently 85 described.

In the operation of making gas, the combustible material is supported on the grate in the usual manner, and when operating on the updraft principle, air is admitted beneath 90 the grate, and the products of the composition pass upward through the shield into the pipe 4, and are removed by the pipe 5 or the pipe 5^a, as the case may be. Outside of the composition zone, gases are distilled from 95 the fuel by the heat and pass upward into the upper part of the generator. These products are received in the pipe 17 and pass thence through the pipes 16, 18 and 19, to a point beneath the grate, and are carried upward by the incoming air and steam when used, through the decomposition zone and into the shield, and are removed with the decomposition products through the pipe 5. When operating on the downdraft principle, 100 the air and steam are admitted through the pipe 5 and the pipe 4 and the shield, to the flue, and the products of decomposition are 105

carried away through the pipe 2^a shown at the bottom of Fig. 1. When operating on the updraft principle, the valve 36 is closed as is also the valve 25, the valves 30 and 31 being open. The distillation products coming through the pipe 17, are thus constrained to travel through the by-pass and are discharged at 20 beneath the grate, passing from thence upward through the decomposition zone to the shield. When operating on the downdraft principle, the draft for the producer is supplied through the pipe 5 as before stated, the valves 25 and 31 are closed, the valves 30 and 36 being open. The distillation products are thus constrained to follow the by-pass, and the pipes 32, 33 and 34 to the pipe 5, passing into the producer through the shield and downwardly through the zone of decomposition.

20 A thermostat 37 of any suitable construction is arranged within the producer outside of the zone of decomposition at any suitable point, the thermostat communicating with a casing 38, provided with a diaphragm 39 having rigid therewith a link 40. The outer end of the link is slotted as at 41, and is engaged by a pin 42 on a lever 43, pivoted by one end to a bracket 44 on the casing and guided in its rising and falling movement by a bracket 46 engaging the free end thereof.

25 A sleeve 47 is slidable on the lever 43, the sleeve being retained in its adjusted position by a set screw 48, and the outer member 49 of a telescoping link is pivoted to the sleeve, the inner member 50 being pivoted to the stem 51 of a valve 52 working in a casing 53, which is provided with an inlet 54, an outlet 55 and an exhaust 56, the inlet being connected with a suitable supply of fluid under pressure. The outlet communicates by a pipe 57, with one end of a cylinder 58, in which is a piston 59, having its piston rod 60 provided at its outer end with a belt shifter, engaging a belt 62 connecting a suitable source of power not shown, with a cone pulley 63 which operates the exhauster. The piston is normally retained in its rearward position by a spring 64 arranged between the end of the cylinder and a collar 65 on the piston.

30 It will be evident from the description, that when the temperature of the point at which the thermostat is placed reaches a predetermined point, the lever 43 will be elevated which will operate the valve 52 to place the inlet 54 in connection with the passage 55, thus admitting fluid under pressure to the end of the cylinder 58, and forcing the piston 59 outwardly, which will shift the belt 62, to reduce the speed of the exhauster 27. A reduction in the speed of the exhauster will decrease the draft through the material outside of the zone of decomposition thus reducing the temperature of the material.

Should the temperature fall below the predetermined point, the outlet 56 will be placed in communication with the exhauster and the spring 64 will move the piston rearwardly to reverse the shifting movement of the belt thus increasing the speed of the ex- 70 hauster.

A valve 66 is arranged within the arm 28 of the by-pass, the valve being provided with a stem 67 pivotally connected with the outer member 68 of a telescoping link the inner member 69 of the link being pivoted to a sleeve 70 adjustable on the lever 43 and retained in adjustable position by a set-screw 71. The members of the telescoping links 49, 51 and 68, 69, are retained in adjusted 80 position by set screws 72.

It will be evident from the description that the thermostat will operate the valve 66 to cut off the draft from the by-pass in addition to operating the exhaust controller, and the parts may be arranged to operate either the exhauster control or the valve 66, or both the valve and the exhauster may be cut out of the circulation by closing the valves 30, 31. The casing 53 is slidable on a rod 73, connected with the casing 38, a set screw 74 being provided for retaining the casing 53 in its adjusted position.

The exhauster 27 is arranged in the by-pass for convenience in cleaning pipe 18, and 95 for cleaning the exhauster and the valve 25 is provided for the same purpose, the said valve being closed except during such cleaning.

In the form of producer shown in Fig. 2, 100 the producer 75 is provided with a cover 76 having a dependent flange 77 engaging a water seal 78 and the cover is provided with a central opening through which passes a feed tube 79, the feed tube being provided 105 with a cover 80 provided with a depending flange 81, engaging the water seal 82. A hood 83 is arranged within the feed tube, the said hood being supported by an arm 84, extending from the side of the tube, and a pipe 110 16^a leads from the hood to a vertical pipe 18^a, which corresponds to the pipe 18 in the form of producer shown in Fig. 1. The products of decomposition when working the decomposing zone between the feed-tube and grate 115 on the up draft principle are removed through the pipe 5^a. The pipe 34 leading from the pipe 5^a corresponds to the pipe 34 in the form shown in Fig. 1. The thermostat 37^a is arranged within the feed tube, and the 120 mechanism which the thermostat controls is in all respects the same as the mechanism shown in Fig. 1. The lower end of the feed tube 79 is provided with a hollow annular extension 86, having a flange 87 bolted or 125 riveted to the feed tube as at 88, and the cavity 89 of the extension is connected by pipes 90 and 91 with some suitable source of

cooling fluid, whereby to prevent over heating of the extension. Above the extension it is lined with refractory material.

When the producer Fig. 2 is operated on the down draft principle the operation of removing the volatiles from the distillation chamber formed within the feed tube 79 is the same as above described when working the producer on the down draft principle, the distilled volatiles being however, in the latter case passed into the space at top of producer through pipe 5^a and down through the decomposing zone entering at the surface of said zone lying between the feed tube 79 and 15 and the wall 75 of the producer.

I claim—

1. A producer comprising a casing, a grate in the casing, a shield above the grate, a pipe leading from the upper part of the casing to 20 the space beneath the grate, said pipe being provided with a by pass, an exhauster in the by pass, a cone pulley in connection with the exhauster, a normally closed valve in the pipe between the ends of the by pass, a pipe 25 leading from the by pass beyond the exhauster and delivering to the shield, a valve for closing said pipe, a valve beyond the by pass for closing the first pipe, a thermostat in the casing in the distillation zone, a cylinder adjacent the producer, a piston in the cylinder, a belt for driving the pulley, a shifter for the belt connected with the piston, means operated by the thermostat for moving the piston in one direction, and a spring for moving 35 it in the reverse direction.

2. A producer comprising a casing, a grate in the casing, a shield above the grate, a collector pipe leading from the shield, a pipe leading from the upper part of the casing, an exhauster in connection with the pipe, means 40 for placing said pipe in communication with the space beneath the grate and with the collector pipe, a thermostat in the casing outside of the decomposing zone line of draft,

and means whereby the thermostat will control the speed of the exhauster. 45

3. A producer comprising a casing, a grate in the casing, a shield above the grate, collector pipes leading from the shield, a pipe leading from the upper part of the casing and 50 delivering beneath the grate, an exhauster in connection with said pipe, a thermostat within the casing above the shield, and means whereby the thermostat will control the speed of the exhauster. 55

4. In a producer, a pipe in communication with the distillation zone and in communication with the decomposing zone, means for rapidly cleaning said pipes, an exhauster in connection with the pipes, a thermostat in 60 the producer, and means whereby the thermostat will control the valve in said pipes and the speed of the exhauster.

5. In a producer, means for withdrawing the products of distillation from the material 65 outside of the zone of decomposition, and for passing said products through the zone of decomposition, and means controlled by the temperature of said material for controlling said means. 70

6. In a producer comprising a casing a grate in the casing, a feed tube above the grate a pipe leading from a shield within the feed tube and communicating with the decomposing zone at such a point that the distillation products removed through the shield in the feed tube must pass through the decomposing zone in order to reach the gas outlet of the producer, an exhauster in connection with the above pipes, a thermostat in 80 the apparatus positioned so as to control the temperature of the distilling fuel in the tube, at a predetermined point by regulation of the draft through the distillation zone. 75
